UNITED STATES PATENT OFFICE.

MARTIN J. SHAUGHNESSY, OF WATERTOWN, NEW YORK, ASSIGNOR TO SHAUGHNESSY KNITTING COMPANY, OF WATERTOWN, NEW YORK, A CORPORATION OF NEW YORK.

COMBINATION-GARMENT.

1,119,994.

Specification of Letters Patent.

Patented Dec. 8, 1914.

Application filed April 9, 1914. Serial No. 830,785.

To all whom it may concern:

Be it known that I, MARTIN J. SHAUGHNESSY, a citizen of the United States, residing at Watertown, county of Jefferson, and State of New York, have invented certain new and useful Improvements in Combination-Garments, of which the following is a specification.

The invention relates to such improvements and consists in the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a front view 20 of my improved combination-garment with the front opened. Fig. 2 is a rear view of the same with the front closed and the drop-seat lowered. Fig. 3 is a horizontal cross-section taken on the broken line 3—3 in Fig. 25 2, with the drop-seat in raised position. Fig. 4 is a vertical cross-section of the garment taken on the broken line 4—4 in Fig. 2.

My invention relates to a combination-garment comprising permanently connected 30 shirt and drawers; and, while adapted for such garments made of various fabrics, it is more particularly adapted for garments made of light-weight highly elastic knitted fabric, such as the open meshed or apertured fabrics commonly used for summer under-wear.

The principal objects of the invention are to better maintain the shape of the garment; and to better protect the body of the wearer.

Referring to the drawings wherein the invention is shown in preferred form, the upper part of the garment comprises a shirt, 1, and the lower part of the garment comprises drawers, 2. In the preferred manner of making the garment, the shirt-body is made of the usual length extending somewhat below the waist-line, and is made open at the front from top to bottom, the sides of the front being buttoned together in the usual manner. The drawers are provided with the usual front opening, 3, the sides of which are buttoned together in the usual manner. The back of the drawers is made with a drop-seat, 4. The front of the drawers is attached along the upper edge to the

body of the shirt at substantially the waist-line, by stitching, 5, whereby the shirt and drawers are permanently connected together. The drop-seat of the drawers is adapted to be supported in raised or closed position by means of buttons, 6, attached to the back of the shirt at substantially the waist-line, which buttons are adapted to engage buttonholes, 7, in the band, 8, along the top-edge of the drop-seat. The lower end 65 of the shirt-body, 1, forms a skirt, 9, which depends from the seam, 5, within the inclosure formed by the drawers. The ends of the skirt formed by the front-opening in the shirt are permanently secured to the 70 drawers along the respective sides of the front-opening, 3, in the drawers. The skirt, 9, thus forms a band which extends entirely around the body of the wearer at all times while the garment is in use, affording protection 75 from drafts whether the drop-seat be open or closed, and affording at all times a protective covering for the front of the person in addition to that afforded by the front of the drawers. This invention also renders the garment more substantial in construction around the waist-portion, which enables the garment to better maintain its shape.

I do not wish to be limited to the above described manner of constructing the garment, as for certain purposes of the invention it is immaterial in what manner the skirt, 9, be formed, so long as it depends within the inclosure formed by the drawers in the manner described, to accomplish the 80 objects of the invention.

What I claim as new and desire to secure by Letters Patent is—

1. A combination-garment comprising permanently connected shirt and drawers having an interiorly located depending skirt extending throughout the circumferential extent of the garment.

2. A combination-garment comprising permanently connected shirt and drawers provided with a front-opening, and having an interior skirt extending around the interior of the garment from one edge of said opening to the other edge thereof, said skirt being connected along its upper edge and along its ends to the body of the garment.

3. A combination-garment comprising permanently connected shirt and drawers, said shirt having the usual body extending below the waist-line, and said drawers being 110

- attached to the shirt-body substantially at the waist-line, the lower end of the shirt-body forming a depending skirt inclosed by the drawers.
5. 4. A combination-garment comprising permanently connected shirt and drawers, said shirt having the usual body, open from top to bottom at its front and extending below the waist-line, said drawers being provided with the usual front-opening and being attached along the upper edge to the body of the shirt substantially at the waist-line, the lower end of the shirt-body forming a depending skirt inclosed by the drawers, the ends of said skirt being secured to the drawers along the respective edges of said front-opening.
5. A combination-garment comprising permanently connected shirt and drawers, said shirt having the usual body, open from top to bottom at its front and extending below the waist-line, said drawers being provided with the usual front-opening and being attached along the upper edge to the body of the shirt at the front thereof substantially at the waist-line, and having a drop-seat detachably connected with the body of the shirt at the back at substantially the waist-line, the lower end of the shirt-body forming a depending skirt inclosed by the drawers, the ends of said skirt being permanently secured to the drawers along the respective sides of said front-opening.
- 20
- 25

shirt at the back at substantially the waist-line, the lower end of the shirt-body forming a depending skirt inclosed by the drawers.

6. A combination-garment comprising permanently connected shirt and drawers, said shirt having the usual body, open from top to bottom at its front and extending below the waist-line, said drawers being provided with the usual front-opening and being attached along the upper edge to the body of the shirt at the front thereof substantially at the waist-line, and having a drop-seat detachably connected with the body of the shirt at the back at substantially the waist-line, the lower end of the shirt-body forming a depending skirt inclosed by the drawers, the ends of said skirt being permanently secured to the drawers along the respective sides of said front-opening.

In testimony whereof, I have hereunto set my hand this 31 day of March, 1914.

MARTIN J. SHAUGHNESSY.
